VETERINARIAN'S ELECTRICALLY HEATED
TWEEZERS FOR REMOVING INSECT PESTS
FROM ANIMALS

Lester J. Crow, 4423 Holly Ave., St. Louis, Mo.

Filed May 13, 1959, Ser. No. 55,887

Term of patent 7 years

(Cl. D83—12)

FIG. 1.

FIG. 2.

FIG. 5

FIG. 3.

FIG. 4.

FIG. 6

Fig. 1 is a side elevational view of a veterinarian's electrically heated tweezers for removing insect pests from animals embodying my new design;

Fig. 2 is a top plan view thereof;

Fig. 3 is a cross sectional view thereof taken on line 3-3 of Fig. 2;

Fig. 4 is a fragmentary cross-sectional view thereof taken on line 4-4 of Fig. 1;

Fig. 5 is a rear elevational view thereof with the front portions omitted for convenience of illustration; and

Fig. 6 is a cross-sectional view thereof taken on line 6-6 of Fig. 2.

I claim:

The ornamental design for a veterinarian's electrically heated tweezers for removing pests from animals, as shown.
